UNITED STATES PATENT OFFICE.

JULIUS C. TOURNIER, OF SCHENECTADY, NEW YORK, ASSIGNOR TO GENERAL ELECTRIC COMPANY, A CORPORATION OF NEW YORK.

ELECTRIC CIGAR-LIGHTER

No. 831,490.

Specification of Letter's Patent

Patented Sept. 18, 1906.

Application filed September 25, 1905. Serial No. 280,104.

To all whom it may concern:

Be it known that I, JULIUS C. TOURNIER, a citizen of the United States, residing at Schenectady, in the county of Schenectady, 5 and State of New York, have invented certain new and useful Improvements in Electric Cigar-Lighters, of which the following is a specification.

This invention relates to igniting devices, 10 and has for its object the provision of a device of this character which is convenient to handle, simple and cheap in construction, and at the same time is perfectly safe, durable, and efficient.

More specifically, my invention relates to 15 igniting devices of the class known as "cigar-lighters," one of my objects being to produce a device of this character that can be conveniently and safely handled and can be 20 brought to the ignition-point quickly and by a simple movement of the hand, as by pressing a button. I also provide a device in which the material which is heated may be renewed after it is finally burned out or otherwise destroyed.

My invention further consists in the feature of construction and in the arrangement and combination of elements hereinafter set forth, and particularly pointed out in the 30 claims annexed to and forming a part of this application.

In the drawings, Figure 1 shows an elevation and partly in section a device embodying my invention. Fig. 2 is a side elevation 35 of the same without the handle and with the casing broken away. Fig. 3 is a view of the casing, and Fig. 4 is a view of the glower-plug. Fig. 5 is a detail of the porcelain base, and Fig. 6 is a section of the same on line 6 6 of Fig. 5.

Referring to the drawings, 1 is a handle for 45 my igniting device, which is to be grasped by the user and may be of any good insulating material, such as wood or hard rubber. A pair of metallic casings 2 and 3, cut away at 2' and 3', are secured to this handle and are arranged so as to telescope one within the other, forming an oval opening through the side. The upper one of these 50 casings 2 forms a cover for my device, while the lower one 3 forms a support for the parts thereof. These casings inclose a receptacle and a switch, both of which are mounted upon the supporting-bracket 4, provided

with a U-shaped portion 5 for securing it to 55 the casings 2 and 3 by means of a screw 6. The bracket is also provided with the angle portion 7, through which it is secured to the handle 1 by means of the stud 8. The socket 9 is secured to the bracket 4 by means of the 60 screws 10. This socket comprises a body-ring 11, provided with an insulating lining 12, on the interior of which is a screw-threaded conducting-lining 13. The base 14, preferably of porcelain, is also secured to the 65 bracket 4 by means of the screws 10 and forms a support for the terminal 15, secured thereto by screw 16 and bent at the angle for engagement with one of the cord-terminals 17 and 18 at 19. The lining 13 forms the 70 other terminal by means of the contact-plate 20, which is electrically connected with the lining. A switch is interposed between the cord-terminals 17 and 18 at contact-plate 20. This switch comprises a button 21 of insulating material inserted in the bracket 4, so as to slide in and out and provided with a 75 collar 22. A spring 23 holds the collar yielding in contact with the plate 20, so that the button 21 normally projects through the cas- 80 ing. A contact 24 is secured to this button and is adapted to engage contact-plate 20 to close the circuit when the button is forced inward, cord-terminal 17 being in electrical connection with contact 24. Casing 2 is pro- 85

vided at its upper end with an opening having an insulating-button 25 therein for supporting the cord-terminals. A heater-plug 26 is adapted to be screwed into the socket 9 and close the circuit from lining 13 to contact 15. This plug forms no part of my invention, and I shall therefore not attempt to describe it in detail. The heating part of this plug consists of a fine wire 26' of resist- 90 ance material inserted in the body of porce- 95 lain or other insulating material 27 and having a screw-threaded conducting-surface 28, which forms one terminal of the resistance-wire, while the contact 29 in the end of the plug forms the other. A sheet of mica is placed 100 over the resistance-wire and a cap 30, provided with an opening, secures the same in place.

The operation of my device will be readily understood from the above description. 105 When it is desired to use my cigar-lighter, the handle is grasped by the hand, while the thumb presses the button 21 inward until

the circuit is closed between contact-plate 20 and contact 24. Current then passes through the cord terminal 18 to contact 15, thence to contact 29, through the resistance-wire in the plug to the lining 13, through the switch, and back to terminal 17. The resistance-wire is thus heated to redness and the radiant heat is sufficient to ignite a cigar on the outside of the mica, thereby forming a convenient and efficient lighter.

What I claim as new, and desire to secure by Letters Patent of the United States, is—

1. An igniting device comprising telescoping casings, a socket carrying circuit-terminals and a switch therefor within the same, said casings being cut away to form an opening into said receptacle.
2. An igniting device comprising telescoping casings, a socket embodying circuit-terminals within the same, said casings being cut away to form an opening into said receptacle.
3. An igniting device comprising a pair of telescoping casings, a socket, a heating unit therefor, and a switch within said casing, said unit and switch projecting through the said casing.
4. An igniting device comprising a pair of telescoping casings, a socket inclosed therein, and a heating unit supported by said receptacle and projecting through the casing.
5. An igniting device comprising a casing, a support therefor, a socket provided with

circuit-terminals mounted in said casing, and a switch within and projecting through the said casing in longitudinal alinement with said socket.

6. An igniting device comprising a casing, a support therefor, a socket provided with circuit-terminals mounted in said casing, a heating unit in said socket, and a switch within and projecting through the said casing in longitudinal alinement with said socket.

7. An igniting device comprising a pair of casings having an opening therein, a support for said casings, a socket provided with circuit-terminals mounted in said opening, a heating unit in said socket, and a switch for closing a circuit through said unit within the casing and projecting through the same in longitudinal alinement with said socket.

8. An igniting device comprising a handle, a pair of telescoping casings mounted thereon and provided with an opening, a heating unit in said opening, and a switch within one of said casings for closing a circuit through said heating unit, said handle, heating unit, and switch all being in longitudinal alinement.

In witness whereof I have hereunto set my hand this 22d day of September, 1905.

JULIUS C. TOURNIER.
